(57) **CLAIM**

The ornamental design for an radiation apparatus, as shown and described.

DESCRIPTION

1. Radiation apparatus

1.1 : Perspective

1.2 : Perspective

1.3 : Front

1.4 : Right

1.5 : Left

1.6 : Top

1.7 : Back

1.8 : Bottom

Fig. 1.1 is a front, right perspective view of a radiation apparatus; fig.1.2 is a back, right perspective view of the radiation apparatus; fig. 1.3 is a front view of the radiation apparatus; fig. 1.4 is a right side view of the radiation apparatus; fig. 1.5 is a left side view of the radiation apparatus; fig. 1.6 is a top view of the radiation apparatus; fig. 1.7 is a backside view of the radiation apparatus; fig. 1.8 is a bottom view of the radiation apparatus.

The portions of the radiation apparatus illustrated in broken lines form no part of the claimed design.
